(57) **ABSTRACT**

A new *Osteospermum* plant particularly distinguished by
yellow flowers and an upright growth habit, is disclosed.

1 Drawing Sheet

1

Genus and species: *Osteospermum ecklonis* Norl.
Variety denomination: 'KLEOE18318'.

BACKGROUND OF THE NEW PLANT

The present invention comprises a new and distinct variety of *Osteospermum*, botanically known as *Osteospermum ecklonis* Norl., and hereinafter referred to by the variety name 'KLEOE18318'. 'KLEOE18318' originated from a cross-pollination conducted in August to September 2012 in Stuttgart, Germany between the proprietary female *Osteospermum* variety 'OE-2011-0679' (unpatented), and the proprietary male *Osteospermum* variety 'OE-2009-0816', also known as 'KLEOE11187' (U.S. Plant Pat. No. 24,034).

The seeds from the cross were sown and plants were grown in a greenhouse for evaluation, where an individual plant designated 'KLEOE18318' was selected from the group of plants in May 2012 in Stuttgart. In June 2012 in Stuttgart, 'KLEOE18318' was first vegetatively propagated by vegetative terminal cuttings. 'KLEOE18318' was found to reproduce true to type in successive generations of asexual propagation via vegetative terminal cuttings.

SUMMARY

The following are the most outstanding and distinguishing characteristics of this new variety when grown under normal horticultural practices in Stuttgart, Germany.

1. Yellow flowers
2. An upright growth habit; and
3. Good branching.

DESCRIPTION OF THE PHOTOGRAPH

This new *Osteospermum* plant is illustrated by the accompanying photograph which shows the plant's overall plant habit including form, foliage, and flowers.

The photograph is of an 8-week-old plant grown in a greenhouse in Stuttgart, Germany in May 2019. The colors

2

shown are as true as can be reasonably obtained by conventional photographic procedures.

DESCRIPTION OF THE NEW VARIETY

The following detailed descriptions set forth the distinctive characteristics of 'KLEOE18318'. The data which define these characteristics were collected in Latina, Italy on May 16, 2019 on plants that had been potted in week 45 of 2018 and cultivated in a plastic greenhouse. Color references are to The R.H.S. Colour Chart of The Royal Horticultural Society of London (R.H.S.), 5th edition (2007).
Classification:

Family.—Asteraceae.

Botanical.—*Osteospermum ecklonis*.

Common.—*Osteospermum*.

Designation.—'KLEOE18318'.

Parentage:

Female parent.—The proprietary *Osteospermum* variety 'OE-2011-0679' (unpatented).

Male parent.—The proprietary *Osteospermum* variety 'KLEOE11187' (U.S. Plant Pat. No. 24,034).

Plant:

Form and habit.—Herbaceous perennial but usually cultivated as an annual; not frost resistant.

Growth habit.—Upright.

Branching habit.—Normal.

Height (from top of soil, including inflorescence).—32.0 cm.

Width (including inflorescences).—35.0 cm.

Propagation type.—Stem cuttings; vegetative terminal tip cuttings.

Time to produce a finished flowering plant.—9 weeks.

Time to initiate and develop roots.—4 weeks.

Root description.—Fine and white, RHS 155A.

Stems:

Total number of branches per plant (calculated at the base of the plant).—9.

Length.—28.0 cm.	5	Peduncle:
Diameter.—0.5 cm.		Length.—2.0 cm.
Internode length.—1.5 cm.		Diameter.—0.1 cm.
Color.—RHS 138B.		Texture.—Smooth with hairs.
Texture.—Smooth but with fine hairs.	10	Color.—RHS 137A.
Anthocyanin.—Absent.		Phyllaries:
Leaves:		Arrangement.—Single.
Arrangement.—Alternate.		Observed quantity per flower.—16.
Shape.—Obovate.		Shape.—Lanceolate.
Apex.—Acute.	15	Apex.—Acute.
Base.—Acute.		Base.—Obtuse.
Margin.—Entire.		Margin.—Entire.
Immature color.—Upper surface: RHS 146A. Lower surface: RHS 146B.		Length.—1.2 cm.
Mature color.—Upper surface: RHS 147A. Lower surface: RHS 146A.	15	Width.—0.2 cm.
Length.—5.4 cm.		Texture.—Upper surface: Smooth with fine hairs.
Width.—1.8 cm.		Lower surface: Smooth.
Texture.—Upper surface: Leathery. Lower surface: Leathery with fine hairs.	20	Color.—Upper surface: RHS 137C. Lower surface: RHS 139B.
Petioles.—Absent.		Reproductive organs:
Venation pattern.—Pinnate.		Androecium.—Location: On disc and ray florets. Stamens: Shape: Filamentous. Quantity: Numerous, 70 to 100. Filament length: 0.7 cm. Filament diameter: 0.1 cm. Anther: Shape: Lanceolate. Color: RHS N92A. Length: 0.2 cm. Diameter: 0.1 cm. Pollen: Color: RHS 25A. Amount: Moderate.
Venation color.—Upper surface: RHS 137D. Lower surface: RHS 137C.	25	Gynoecium.—Location: On the phyllary. Pistils: Number: Numerous, 50 to 70. Length: 0.8 cm. Diameter: 0.2 cm. Stigma: Color: RHS 18D. Shape: Tapering filamentous and split in two parts. Length: 0.2 cm. Diameter: 0.2 cm. Style: Color: RHS 156D. Length: 0.4 cm. Diameter: 0.1 cm.
Flower buds:		Fruit and seed set: None observed to date.
Shape.—Round-ovoid.		Disease and pest/insect resistance: No disease and pest/insect resistance observed.
Length.—1.0 cm.		
Diameter.—1.1 cm.		
Color (at tight bud just before the ray florets unfold).—RHS 137D.	30	
Inflorescence:		COMPARISON WITH PARENTAL LINES AND KNOWN VARIETY
Type.—Single.		
Blooming habit.—Upright, with longer flower stems.	35	‘KLEOE18318’ is a distinct variety of <i>Osteospermum</i> and is distinguished from its parents as described in Table 1.
Quantity of inflorescences per plant.—12.		
Lastingness of the inflorescences on the plant.—10 to 15 days.		
Fragrance.—Present.		
Inflorescence diameter.—7.0 cm.	40	TABLE 1
Inflorescence depth.—1.0 cm.		Comparison with Parental Lines
Disc diameter.—1.3 cm.		
Disc floret:		
Quantity per inflorescence.—22.		
Shape.—Tubular.	45	
Tube color.—Closed: RHS 12A. Mature: RHS 9A.		Characteristic 'KLEOE18318' Female Parent Male Parent
Length.—0.7 cm.		Earliness Early 'OE-2011-0679' 'OE-2009-0816'
Diameter (at apex).—0.2 cm.		Branching Good Medium early Medium early
Apex.—Acute.		
Apex color.—RHS 92A.	50	
Base.—Acute.		‘KLEOE18318’ is most similar to the commercial <i>Osteospermum</i> variety ‘Flower Power Pink’ (KLEOE17007). Differences between the varieties are described in Table 2.
Base color.—RHS 10B.		
Margin.—Entire.		
Ray floret:		
Quantity per inflorescence.—23.	55	TABLE 2
Shape.—Oblanceolate.		Comparison with Similar Variety
Color.—Upper surface: RHS 12B. Lower surface: RHS 12A.		
Length.—3.6 cm.		
Width.—1.0 cm.		
Apex.—Acute.	60	
Base.—Acute.		
Margin.—Entire.		
Texture.—Upper surface: Smooth. Lower surface: Smooth, shiny.	65	
		We claim:
		1. A new and distinct variety of <i>Osteospermum</i> plant designated ‘KLEOE18318’ as illustrated and described herein.
